(57) **CLAIM**

We claim the ornamental design for a modular power unit, as shown and described.

DESCRIPTION

FIG. 1 is a perspective view of a modular power unit embodying the invention.

FIG. 2 is a first side view of the modular power unit of FIG. 1.

FIG. 3 is a second side view of the modular power unit of FIG. 1.

FIG. 4 is a first end view of the modular power unit of FIG. 1.

FIG. 5 is a second end view of the modular power unit of FIG. 1.

FIG. 6 is a top view of the modular power unit of FIG. 1; and,

FIG. 7 is a bottom view of the modular power unit of FIG. 1.

The broken lines shown in the figures represent environmental subject matter and form no part of the claimed design.
